UNITED STATES PATENT OFFICE.

PETER HOGSTROM, OF NEW YORK, N. Y.

ROOF-DOOR.

1,380,207.

Specification of Letters Patent.

Patented May 31, 1921.

Application filed May 5, 1920. Serial No. 379,101.

To all whom it may concern:

Be it known that I, PETER HOGSTROM, a citizen of the United States, and a resident of the city of New York, Long Island City, 5 borough of Queens, in the county of Queens and State of New York, have invented a new and Improved Roof-Door, of which the following is a description.

The importance of opening a roof door 10 when a building is in flames is well recognized. One of the first duties of the truck companies of the fire department is to see that the roof door is open to thereby prevent the curling or mushrooming of the flames 15 downwardly with destructive results to the parts of the building below the floor on which the fire occurs.

It is an object of my invention to provide 20 a roof door that will automatically and unfailingly open under a predetermined heat.

A further object of the invention is to utilize the weight of the door and cause it to gravitationally swing to the open position and to normally restrain the door in the 25 closed position subject to a fusible element.

The invention also has for an important 30 object to provide for the optionally manual raising and lowering of the roof door without affecting the automatic control of the same.

A more specific object of the invention is to provide an embodiment of the invention reflecting practical considerations with respect to strength and durability with simplicity of construction as well as to promote 35 convenience of installation.

Reference is to be had to the accompanying drawings forming a part of this specification, it being understood that the drawings are merely illustrative of practical examples of the invention.

Figure 1 is a longitudinal vertical section of a roof door embodying my invention;

Fig. 2 is a partly sectional side elevation 40 thereof;

Fig. 3 is a transverse vertical section;

Fig. 4 is a plan view;

Fig. 5 is an inverted plan view;

Fig. 6 is a transverse vertical section 50 showing the invention in another form.

In carrying out my invention in accordance with the example illustrated in Figs. 1 to 5, the curb 10 on the roof 11 at the scuttle or skylight, may be of any approved 55 construction. My improved door includes

a frame 12 which is hinged at one end as at 13 to the curb 10 or equivalent structure so as to be optionally swung outwardly for the opening of the door in the ordinary use thereof. Within the frame 12 I provide an 60 inwardly swingable door 14 which as will be readily understood, may be glazed or otherwise. Said door 14 is hinged at one end as at 15 to the frame 12 to swing vertically as a drop door, relatively to said frame. The 65 frame 12 is covered with a suitable sheathing 16 which may, as shown, extend over the hinged end of said frame as at 16^a to exclude the rain and the drop door 14 has a sheathing 17 which extends beyond the 70 hinge 15 of said drop door and beyond the frame 12 as indicated at 20, said end 20 and the end 16^a being curved downwardly. At the sides of the door 14, the frame 12 and said door have coacting elements to exclude 75 water, the sheathing 16 being formed into inverted channels 18 and adapted to receive vertical flanges 19 on the sheathing 17 when the door 14 is in the raised position.

The door 14 will have a tendency to 80 gravitationally move to the open position swinging on the hinge or hinges 15 and relatively to the frame 12 which remains in position as said drop door opens. In order to restrain the door 14 in the raised position, holder means at the under side thereof, subject to a predetermined heat, is provided and as here shown includes short chain lengths 21, 22 terminating at their adjacent ends in separable elements 23 overlapping 90 each other and united by a fusible solder. The opposite end of one chain 21 is secured to the door 14, there being shown a fitting 24 to which said chain end is secured, said fitting being suitably fastened in fixed position to a cleat 25 on the under side of said door or other fixed part thereof. The end of the chain length 22 opposite the element 23 thereon is secured to a movable element 26 here shown as a frame hinged as at 27 100 to a cleat 28 on the under side of frame 12 adjacent to the free end of the door 14. Additional cleats 29, 30 are preferably provided for strength at the under side of the door 14, one of the cleats being at the free 105 edge of the door and provided with a wear element 31 with which the swingable element 26 may contact. Thus, in the drawing of the chain lengths 21, 22, together, to be joined by the soldering of the element 23, the 110

hinged element 26 will bear against the cleat 30 at the wear projections 31 and exert a tightening leverage against the door 14.

With the above-described construction, it will be obvious that the complete door including the frame 12 may be swung outwardly whenever desired and without disturbing the automatic control of the inwardly opening door 14. With the door structure in the closed position should fire occur developing a heat sufficient to fuse the substance uniting the elements 23, the latter will separate and permit the door 14 to automatically swing inwardly thereby venting the building to which the structure is applied.

Fig. 6 represents another known form of skylight structure in which a vertical side door is provided, embodying my invention, there being a frame 12^a hinged as at 13^a to swing outwardly with the inwardly swinging door 14^a and the latter being hinged at its lower edge as at 15^a, to said frame 12^a. With the vertical door, the illustrated arrangement may be adopted, the frame 12^a being hinged at the top as at 13^a to a depending member 10^b on the fixed roof structure 10^a at the scuttle or skylight, the door 14^a being hinged at its lower edge as at 15^a to said frame. A latch bolt 32 having a projection 32^c forming a finger-hold may be provided on member 10^b, as well as a keeper 32^a on frame 12^a to receive the latch bolt, the withdrawal of the bolt from said keeper serving to release said frame 12^a and permit it to be swung outwardly with the door 14^a. The door 14^a may have any suitable latch to normally hold it against swinging inward, there being shown in the illustrated example 40 a ball 32^b under pressure of a spring 32^d housed in a pocket 32^e in the upper edge of door 14^a, the ball being adapted to spring into a depression 32^f in the opposed edge of frame 12^a.

45 The automatic controlling means in the form shown in Fig. 6 is modified to the extent that a chain length 21^a is secured at one end to a depending chain length 22^a suspended from the united elements 23 which may be the same as previously described, said elements being suspended from the top of the fixed structure 10^a at the scuttle or skylight opening, there being illustrated for the purpose a short chain 22^b secured to the adjacent element 23 and to the structure 10^a by an eye 22^c. The depending chain 22^a has a weight 33 hung thereon and therefore indirectly suspended from the lower one of the soldered elements 23. That end 60 of the chain 21^a opposite the weighted suspended chain 22^a is connected with the door 14^a as by an eye 26^a.

With the construction shown in Fig. 6 the complete door composed of the frame 12^a and swingable door 14^a may swing outwardly on the hinge 15^a for opening the door for ordinary purposes. This is so because the connection of the chain 21^a with door 14^a is close to hinge 15^a and therefore the point of connection moves through but an arc of small radius in the outward opening of the door. Should fire occur and heat develop sufficiently for fusing the elements 23, the weight 33 will drop and through the connection 21^a swing the door 14^a inwardly, the weight serving to overcome the frictional engagement of the ball catch 32^a with the frame 12^a at the recess 32^e.

With the described arrangement of the door 14^a its own weight causes the inward movement when said door is released. With the described arrangement of the door 14^a, its own weight plus that of weight 33 and chain 21^a, considered together as a unitary potential weight, the said door 85 opens automatically under said combined unitary weight distributed as described.

I would state in conclusion that while the illustrated examples constitute practical embodiments of my invention, I do not limit myself strictly to the mechanical details herein illustrated, since manifestly the same can be considerably varied without departure from the spirit of the invention as defined in the appended claims.

Having thus described my invention, I claim:

1. A roof door structure including a frame, means to hingedly secure the frame to swing outwardly, and a door hinged in said frame to swing outwardly therewith and to swing inwardly independently of said frame.

2. A roof door structure including a frame, means to hingedly secure the frame to swing outwardly, and a door hinged in said frame to swing outwardly, and a door hinged in said frame to swing outwardly therewith and to swing inwardly independently of said frame; together with holding means normally restraining said inwardly swinging door against movement relatively to said frame, said means being subject to a predetermined heat for releasing the inwardly swinging door.

3. A roof door structure including a frame, means to hinge said frame to swing outwardly, a door hinged in said frame to swing inwardly independent of the frame and adapted to swing outwardly with said frame, and means subject to a predetermined heat and serving to restrain said inwardly swinging door against opening movement.

PETER HOGSTROM.
